DESIGN FOR A GLASS BOTTLE

Lawrence J. Kihn, Pittsburgh, Pa., assignor to
J. T. & A. Hamilton Company, a corporation of Pennsylvania

Application February 27, 1937, Serial No. 67,896

Term of patent 3½ years

To whom it may concern:

Be it known that I, Lawrence J. Kihn, a citizen of the United States, residing in Pittsburgh, in the county of Allegheny and State of Pennsylvania, have invented a new, original, and ornamental Design for a Glass Bottle, of which the following is a specification, reference being had to the accompanying drawing, forming part thereof.

In the drawing: The single illustrative figure is an elevational view of a glass bottle showing my design.

I claim:

The ornamental design for a glass bottle substantially as shown.

LAWRENCE J. KIHN.
